A. GUIDUCCI

JACK HAMMER REST

Filed Feb. 25, 1927

INVENTOR.

ANDREA GUIDUCCI,

BY

Geo C. Tew

ATTORNEY.

UNITED STATES PATENT OFFICE.

ANDREA GUIDUCCI, OF PECKVILLE, PENNSYLVANIA.

JACK-HAMMER REST.

Application filed February 25, 1927. Serial No. 170,925.

My present invention, in its broad aspect, has reference to improvements in supports; and more particularly it is my purpose to provide a support for jack hammers, and for power boring and drilling tools, and to this end I have provided unique and novel means in conjunction with the support for powerfully urging the tool bearing end of the support toward the work, or in the direction in which the tool is to be fed, thereby eliminating the arduous labor heretofore characterizing the forcing of a power hammer, drill or the like upon or into the work by the operator.

Other equally important objects of my invention may be briefly defined as follows; first, I have attained through the instrumentality of a weight and a lateral arm on the support on which the weight is carried, an off-center distribution of a load on the support toward the work, thereby to powerfully urge the tool bearing end of the support toward the work to feed the tool into the work; second, I have provided means for adjusting the height of the support, and third, a simple and novel foot for the support enables me to pinch or pack the support toward the work as the tool feeds into the work under the influence of the weight.

In the drawing wherein, I have shown the principal embodiment of my invention:

Figure 1 is an assembly view of my support, a tool being shown conventionally thereon, and illustrating its application to the work.

Figure 2 is a sectional view of my support, and

Figure 3 is a detail view of the foot of my support.

In the drawings, like characters of reference are used throughout the several views to designate like or similar parts.

The numeral (1) designates a base which may be a floor or the like, and (2) a cement wall or the like in which it is desired to bore or drill an opening by means of a power or jack-hammer, or drill, or the like which is conventionally shown at (3).

The jack, or power hammer, or the like (3) is supported in position by an adjustable and sectional standard (4). The standard (4) has a hollow or tubular body (5), the ends of which are open to receive upper and lower rods, respectively designated (6) and (7). The free end of the

upper rod is formed with a bracket or saddle (8) which carries the tool (3), and the remaining end of the rod is screw threaded as at (9) to a point near the middle thereof to receive thereon a nut (10) whereby the rod is fed into and out of the tubular body (5). The nut has a pivoted operating handle (11) therein so that it may be readily manipulated. A stop screw (12) moving in a slot (13) in the body (5) prevents the rod (6) from being wholly detached, and also prevents rotational movement thereof with respect to the body.

The lower rod (7) is not screw threaded, but is provided with spaced apart openings (14) through any one of which a shackled key (15) is adapted to be disposed to adjust the exposed length of the rod with respect to the body (5). The free end of the rod is bifurcated as at (16) to provide prongs (17) constituting the feet of the support.

Between the screw threaded portion (9) and saddle (8) of the rod (6) is a lateral arm (18) on which is removably carried a relatively heavy weight (19), a hook (20) or the like being provided for that purpose.

In operation the support is set up with the arm (18) directed toward the work (2), and the tool mounted in the saddle (8). The support is now properly adjusted in height to position the tool and a small hole is bored as a "feeder" whereupon the weight (19) is hung on the arm to force the tool into the work. As the tool is fed into the work the support is gradually moved toward the work by pinching or jacking the foot toward the work by means of a crow-bar or the like (21). It is therefore only necessary for an operator to guide the tool (no labor or pressure upon the tool being necessary) to feed it into the work, one hand can be used for this purpose while with the other hand the crow-bar can be manipulated to move the foot toward the work.

While in the foregoing I have shown and described a specific embodiment of my invention, I do not desire to be limited in the broad concept of my invention, except as may be indicated by the scope of the subjoined claims:

I claim:

1. A support for power tools comprising a supporting standard, an arm laterally carried thereby, and a weight on the arm for swinging the standard toward the work.

2. A support for power tools comprising a supporting standard, an arm laterally carried thereby, a weight on the arm for swinging the standard toward the work, and said standard being movably mounted with respect to a base to permit adjustment of the standard as a whole toward or away from the work.
3. A support for power tools comprising 10 a sectional supporting standard, means for adjusting the height of the standard, an arm laterally extending from the standard, and a weight on the arm for swinging the standard toward the work.
4. A support for power tools comprising 15 a tubular standard, members adjustably carried within the standard and extending from

its ends, one of said members carrying the tool and the other member formed with a supporting foot, an arm extending laterally from one of said members, and a weight on the arm for swinging the standard toward the work. 20

5. A support for power tools comprising sectional standard 5, said sections being adjustable with respect to each other to regulate the height of the standard, a weight, and means for supporting said weight from one of said sections and off-center with respect to the standard thereby to swing the standard toward the work. 25

In testimony whereof I affix my signature. 30

ANDREA GUIDUCCI.
